(57) **CLAIM**

The ornamental design for a handle portion of a latch, as shown and described.

DESCRIPTION

FIG. 1 shows a perspective view of a handle portion of a latch according to our invention;

FIG. 2 shows another perspective view of the handle portion of a latch shown in FIG. 1;

FIG. 3 shows a right side elevational view thereof, a left side elevational view not being shown as it is a mirror image of the right side elevational view;

FIG. 4 shows a top plan view thereof;

FIG. 5 shows a bottom plan view thereof;

FIG. 6 shows a front elevational view thereof; and,

FIG. 7 shows a rear elevational view thereof.

The portions of the article in broken lines are shown for illustrative purposes only and form no part of the claimed design.
